TOY SPINNING TOP

Peter Balleis, 55 Hermann-Lons-Strasse,
Zirndorf, near Nuremberg, Germany

Filed Sept. 24, 1971, Ser. No. 183,725

Claims priority, application Germany July 28, 1971

Term of patent 7 years

Int. Cl. D21—01
U.S. Cl. D34—15 CC

The figure is a perspective view of a toy spinning top showing my new design.

The base is conventional and the essential features of my design reside in the portion within the transparent dome.

I claim:

The ornamental design for a toy spinning top, as shown and described.
